G. C. WATSON,

COMBINATION OF BUFFER AND BED.
FILED OCT. 9, 1922.

UNITED STATES PATENT OFFICE.

GROVER C. WATSON, OF SABINAL, TEXAS.

COMBINATION OF BUFFER AND BED.

Application filed October 9, 1922. Serial No. 593,264.

To all whom it may concern:

Be it known that I, GROVER C. WATSON, a citizen of the United States, residing at Sabinal, in the county of Uvalde and State 5 of Texas, have invented certain new and useful Improvements in Combination of Buffers and Beds, of which the following is a specification.

My invention relates to buffers and beds 10 and more particularly to a combination buffer bed; and the object is to provide an improved buffer for motor vehicles which can be readily converted into a bed or couch and which will be economical because it can be 15 made at small cost and sold at small cost and which will answer all the purposes of any other buffer and which will be a convenience to travelers, hunting parties, laborers, and like purposes. One of the advan- 20 tages of the invention is that it can be used both on the front and on the rear of the vehicles. Other objects and advantages 25 will be fully explained in the following description and the invention will be more particularly pointed out in the claims.

Reference is had to the accompanying drawings which form a part of this application.

Fig. 1 is a plan view of the buffer and bed folded and an outline dotted, showing the position when unfolded to form a couch. Fig. 2 is a plan view of the device detached from the vehicle frame and unfolded to 35 form a couch or bed. Fig. 3 is an enlarged detail sectional view, taken on the line 3-3 of Fig. 1.

Similar characters of reference are used to indicate the same parts throughout the several views.

40 The improved device has a buffer bar 1 in form similar to buffers of ordinary type. This buffer 1 is pivotally connected to a side bar 2 near one end and pivotally connected to a side bar 3 near its other end. The 45 device is attached to a vehicle frame by a bar 4 which forms a part of the bed or couch frame. The buffer 1 also forms a part of the bed or couch frame. Hangers 5 are riveted to the bar 4 and detachably 50 bolted to the frame members 6 of the vehicle. Side bars 7 are pivotally connected to each other and pivotally connected to the bar 4, Fig. 3 showing the manner of hinging the bars 3 and 7 to the bars 1 and 4 re-

spectively. The pivot pins 8 project above 55 the hinge connections and serve as pegs or holders for a sheet 9 of canvas or other strong material which forms a part of the bed or couch.

The hangers 5 serve to support one end 60 of the bed and legs 10 are pivotally connected to the bar or buffer 1 to support the outer end of the bed. The legs 10 also serve to hold the buffer 1, bar 4, bars 7, and bar 2 in the folded position, the bars or legs 10 65 having cut-outs in the sides adjacent to these bars, as shown in Fig. 3. The shoulder 11 will securely lock all the bars together when the bars are folded. The bars form a good buffer and may be used on the front of the 70 vehicle for a front buffer or attached to the rear part of the vehicle for a rear buffer. When the bars are unfolded and supported by the legs 10, any suitable bedding may be 75 used to form the bed or couch.

What I claim, is,—

1. A combination buffer and bed comprising a bar stationarily attached to a vehicle frame, a buffer, foldable side bars pivotally connected to each other and to said station- 80 ary bar and to said buffer, and legs pivotally connected to said buffer.

2. A combination buffer and bed comprising a bar, means for attaching said bar rigidly to a vehicle frame, foldable side bars 85 pivotally connected to each other and to said stationary bar, a buffer pivotally connected to said side bars, and legs pivotally connected to said buffer to support said buffer when said side bars are unfolded to 90 form a bed.

3. A combination buffer and bed comprising a bar, hangers for making said bar rigid with a vehicle frame, foldable extension bars pivotally connected to said rigid 95 bar and to each other, a buffer pivotally connected to said extension bars, legs pivotally connected to said buffer and adapted to support said buffer when extended to form a bed and foldable on said bars and buffer and 100 provided with shoulders for locking said bars and buffer rigidly together when said bars and buffer are folded to form a buffer for a vehicle.

4. A combination buffer and bed comprising a bar, hangers for attaching said bar rigidly to a vehicle frame, extension bars and pivot pins for connecting said extension 105

bars to each other and to said rigid bar, a
buffer and pivot pins connecting said buffer
to said extension bars, and legs pivotally
connected to said buffer to form supports
when said buffer is extended to form a bed
and foldable on said buffer and bars for
locking said buffer and bars rigidly together

when folded, said pins forming means for
attaching bedding to said bars when used
for a bed.

In testimony whereof, I set my hand, this
30th day of September, 1922.

GROVER C. WATSON.
